ATTORNEYS

UNITED STATES PATENT OFFICE.

CHARLES C. SPREEN, OF DETROIT, MICHIGAN, ASSIGNOR TO ELECTRIC REFRIGERATION CORPORATION, OF DETROIT, MICHIGAN, A CORPORATION OF MICHIGAN.

MECHANICAL REFRIGERATION.

Application filed January 29, 1927. Serial No. 164,424.

My invention relates to mechanical refrigeration, and particularly to refrigerant expansion units for mechanical refrigerating apparatus, and the principal object of my invention is to provide new and improved refrigerant expansion units of this type. In the drawings accompanying this specification and forming a part of this application I have shown, for purposes of illustration, two forms which my invention may assume, and in the drawings:

Figure 1 is a front elevation of one embodiment of my invention,

Figure 2 is a section on the line 2—2 of Figure 1,

Figure 3 is a section on the line 3—3 of Figure 1, while

Figure 4 is a fragmentary view similar to Figure 2 showing a variant form.

The embodiment of my invention herein shown comprises a refrigerator cabinet 11 having a refrigerating compartment 12 in which is supported my improved expansion unit 13 comprising a tank body formed of

two substantially semi-cylindrical sheet metal plates 14 and 15 having reinforcing ribs 16, having relatively broad flanges 17 and 18 about a portion of their peripheries, and so shaped that when the flanges 17 and

18 are placed in contact and secured together by brazing, welding, or other suitable means there is formed a receptacle 25 having one open end and a relatively broad flange seam 19 extending outwardly therefrom except at

the open end. The unit 13 is completed by a closure 20 which carries the float valve mechanism 21 and is secured in the open end of the receptacle 25 by any suitable means, such as brazing, or soldering. The flange 19

is provided with apertures 22 adapted to be engaged by bolts 23 depending from the top wall 24 of the compartment 12 for supporting the unit within such compartment.

In the variation shown in Figure 4 the tank 30 comprises semi-cylindrical plates 26 and 27 provided with relatively narrow interlocking flanges forming a relatively narrow seam 28, and is designed for use in a cabinet having supporting means different from that shown in Figure 1, for example a cradle 29 extending below the tank 30.

From the above disclosure it will be obvious to those skilled in the art that I have provided new and improved refrigerant expansion units for mechanical refrigerating apparatus.

At the same time it will be obvious to those skilled in the art that the embodiment of my invention herein shown and described may be variously changed and modified without departing from the spirit of my invention or sacrificing the advantages thereof, and it therefore will be understood that the disclosure herein is illustrative only, and that my invention is not limited thereto.

I claim:

1. In a mechanical refrigerating system, a refrigerant expander unit including a container for refrigerant comprising two cupped sheet metal plates having their peripheral edges joined throughout part of their extent to form an open end receptacle, and a member joining said cupped sheets over the remainder of their peripheries to form a closure for said open end of said receptacle.

2. In a mechanical refrigerating system, a refrigerant expander unit including a float valve tank comprising two cupped sheet metal plates having their peripheral edges joined throughout part of their extent to form an open end float valve receptacle, a member joining said cupped sheets over the remainder of their peripheries to form a closure for said open end receptacle, and a shut-off valve means for said tank mounted on said member.

3. In a mechanical refrigerating system, a refrigerant expander unit including a container for refrigerant comprising two cupped sheet metal plates having their peripheral edges joined directly together throughout part of their extent to form a receptacle having one open end, and means for closing said open end.

4. In a mechanical refrigerating system, a refrigerant expander unit including a container for refrigerant comprising two cupped sheet metal plates having pressed in reinforcing ribs, joined at their peripheral edges, and affording a chamber therebetween, to thus form said container.

5. In a mechanical refrigerating system, a refrigerant expander unit including a container for refrigerant comprising two sheet metal plates joined at their peripheral edges and affording a chamber therebetween, to thus form said container, and having said edges extended outwardly from said container for at least part of their extent, said outwardly extended edges being provided with apertures for association with supporting means.
- 10
- In testimony whereof I hereunto affix my signature.

CHARLES C. SPREEN.
